UNITED STATES PATENT OFFICE

123,430

DESIGN FOR A COMBINED BRUSH AND COMB

Dorothy Hertzberg, Detroit, Mich.

Application May 8, 1940, Serial No. 92,223

Term of patent 7 years

To all whom it may concern:

Be it known that I, Dorothy Hertzberg, a citizen of the United States, residing at Detroit, in the county of Wayne and State of Michigan, have invented a new, original, and ornamental Design for a Combined Brush and Comb, for which the following is a specification, reference being had to the accompanying drawing, forming part thereof in which:

bristles omitted for convenience of illustration;
and

I claim:

The ornamental design for a combined brush and comb, substantially as shown.

DOROTHY HERTZBERG.
